G. F. VOIGHT

WIRE FASTENER

Filed August 10, 1925

INVENTOR:

George F. Voight

UNITED STATES PATENT OFFICE.

GEORGE F. VOIGHT, OF OAKLAND, CALIFORNIA.

WIRE FASTENER.

Application filed August 10, 1925. Serial No. 49,298.

To all whom it may concern:

Be it known that I, GEORGE F. VOIGHT, a citizen of the United States, residing at Oakland, in the county of Alameda and 5 State of California, have invented new and useful Improvements in Wire Fasteners, of which the following is a specification.

My invention relates to improvements in wire fasteners particularly adapted for attaching metal lath in outstanding relation to the wall sheathing of stucco structures, although also useful for other purposes, and in which a spacing element is carried on a nail or driven element.

15 One of the objects of the present invention is the provision of a spacing element of novel form; a further object is the provision of novel means for normally frictionally locking the spacing element on the 20 forward end of the nail to resist movement relative thereto, but slideable thereon for cooperation with the head of the nail for binding the lath therebetween, when the nail is operatively driven in the wall 25 sheathing against which the spacing element is seated.

With the foregoing and still further objects and purposes in view which will appear as the description proceeds, my invention resides in the combination and arrangement of parts and in the details of construction hereinafter described and claimed, it being understood that changes in the precise embodiment of the invention herein disclosed can be made within the scope of what is claimed without departing from the spirit of the invention.

In the accompanying drawings—

Figure 1 is a view in elevation of a wire 40 fastener constructed in accordance with my invention, disposed against the wall sheathing of a structure preparatory to driving it thereinto, and a section of lath wire;

Figure 2 is a side elevation of one of the 45 present fasteners attached at a portion of the wall sheathing, the latter shown in section, and a cross section of the metal lath confined between the nail head and the spacing elements;

50 Figure 3 is a view similar to Fig. 2, but with the spacing element shown sectionally;

Figure 4 is a view on line 4'-4' of Fig. 2;

Figure 5 is a view on line 5'-5' of Fig. 2; 55 Figure 6 is a median sectional elevation along one diameter of the spacing element, a side elevation of the lower portion of the nail, and a sectional view of a fragmental portion of the wall sheathing.

Figure 7 is a stamping showing one step 60 in the construction of the spacing element.

Referring to the drawings in detail, throughout which like reference characters designate like parts:

The numerals 1, 2 and 3 designate the wall 65 sheathing, metal lath, and wire fastener, respectively.

The wall sheathing 1, which comprises, preferably, the usual boards nailed across the stud and other frame timbers forming the frame-work of the walls of stucco structures, forms the backing for the stucco composition (not shown) and the support to which the metal lath 2 is attached in outstanding relation by means of the wire fasteners 3.

70 The lath 2, which may comprise any suitable wire fabric, or the like, including the wire netting commonly known as "poultry netting", forms the reinforcement for the stucco composition, the latter being applied 75 by spreading it on the wall sheathing 1 and on and around the lath 2 until a stucco coat of suitable thickness is obtained.

The wire fastener 3 comprises a nail 4 provided with the usual head 5, and a spacing element 6. The latter comprising an oblong strip of sheet metal bowed upwardly intermediate its ends in the form of an arch having relatively long side limbs 7, which terminate at their lower ends in outwardly extending supporting lips 8, which are adapted to seat against the wall sheathing 1 and form supports for the side limbs 7.

90 The crown of the arch is preferably con- 95 cavo-convex in the plane of the side limbs 7, and is provided at its apex adjacent the side edges of the spacing element, with upwardly struck lath retaining humps or projections 9.

100 10 designates an opening extending vertically through the apex of the arch in the

plane of the projections 9 and, preferably, equi-distant from each.

The side limbs 7 are provided, each, with a pair of spaced conical indents 11 struck thereinto from the outer side, thereby forming corresponding projections 12 on the inner side. These indents and resultant projections are preferably so arranged that those on one of said side limbs will register axially with those on the opposite side limb. Two of which registering projections being disposed on one side of the nail 4, and the remaining two on the opposite side thereof.

The spacing element 6 is intended to be "factory assembled" on the forward end of the nail 4, as shown in Figs. 1 and 6, and carried thereon, thereby facilitating the application of the fastener to the lath for attaching it to the wall sheathing. It is therefore preferable to arrange the distance between the side limbs 7, relative to the diameter of the nail, so that the latter will bear against the former with sufficient pressure to resist removal therefrom, but slideable therebetween when the spacing element is seated against the wall sheathing and the nail operatively driven therein.

To apply my improved fastener, the nail 4 is grasped by its upper end and its forward end together with the spacing element projected through a suitable mesh of the lath and against the face of the wall sheathing. It is next manipulated so as to bring the nail along one side of one of the wires forming the mesh, with one of the projections 9 disposed on the opposite side thereof (see Fig. 1). The nail is then driven into the wall sheathing until the head 5 engages and binds the lath down firmly on the apex of the spacing element, between one of the projections 9 and the nail (see Figs. 2 and 3). The fasteners may be disposed at such intervals along the lath as found best suited to the work to be performed.

It is to be understood that, if preferred, the spacing element may be assembled on the nail at a distance thereon above the point.

I claim:

1. A wire fastener comprising, a spacing element formed of a strip of flat metal bent flat-ways longitudinally, thereby forming an apex having an opening therethrough and a pair of parallel side-limbs having their free ends bent outwardly in opposite directions to form a pair of supporting lips, and a cooperating nail projecting through said opening and between said side-limbs, said nail bearing against said side-limbs below said opening to normally resist removal from therebetween but longitudinally slideably along the inner face sides of said side-limbs when said nail is operatively driven in a support against which said supporting lips are seated.

2. A wire fastener comprising, a spacing element formed of a strip of sheet metal bent flat-ways intermediate its ends, thereby forming an apex, said apex having an opening, and a pair of side-limbs disposed in parallelism, and a cooperating nail projecting through said opening and between said side-limbs and bearing against the latter substantially from the upper to the lower ends thereof, whereby said nail is normally held in general axial alignment with said spacing element, said nail adapted to be forcibly moved longitudinally between said side-limbs for projecting it into a support for binding said spacing element thereagainst. 75

3. A wire fastener of the character described, comprising, a spacing element formed of a strip of flat metal bent intermediate its ends to form an apex and a pair of spaced side-limbs terminating at their free ends in opposed supporting lips, and a cooperating nail projecting vertically through said apex and between said side-limbs and bearing against the inner face sides of the latter below said apex, said side-limbs having means on the inner sides in bearing engagement with opposite sides of said nail. 80

4. A wire fastener comprising, a spacing element formed of sheet metal and bowed flat-ways longitudinally in the form of a loop, the apex of the latter provided with an opening, and a cooperating nail projecting longitudinally through said loop through said opening, said loop having projections on its inner side bearing against said nail a distance below said opening. 95

5. In combination, a spacing element comprising a strip of flat metal bowed flat-ways longitudinally in the form of an arch having parallel spaced side limbs, a pair of spaced projections on the inner side of one of said side limbs, and a cooperating nail projecting through the apex of the spacing element and between said side limbs and between said projections, said nail having a head for engaging and binding a lath wire on said apex. 105

6. In combination, a spacing element comprising a strip of flat metal bent flat-ways intermediate its ends in the form of an arch having spaced side limbs disposed in parallelism, each of said side limbs having a pair of projections on its inner side, and a cooperating nail projecting through the apex of said arch and between said pairs of projections and to bear against the latter to normally resist movement relative thereto, but operatively slideable therebetween when driven in a support against which said spacing element is seated. 115

7. In combination, a spacing element comprising a strip of flat metal bent flat-ways longitudinally in the form of a loop having parallel spaced side members, a pair of spaced projections on the inner side of one 120

of said side members, a pair of spaced projections on the inner side of the opposite side member, said last named projections registering axially with said first named projections, and a nail projecting through the apex of said loop and between each pair of said projections, said apex having a lath

retaining projection on each side of said nail and in a plane therewith, said nail having a head adapted to bind a lath wire on 10 said apex between one of said last named projections and said nail.

GEORGE F. VOIGHT.
